METHOD AND APPARATUS FOR PLYING
STRANDSSeddon C. Nelson, Front Royal, Va., assignor to
American Viscose Corporation, Wilmington,
Del., a corporation of Delaware

Application March 1, 1945, Serial No. 580,409

25 Claims. (Cl. 57—58)

1

The present invention relates to methods and apparatus for twisting two or more strands together into the form of a plied or doubled construction.

It has heretofore been suggested to twist together two or more yarns or other strands by causing one strand to be rotated about the supply package for the other strand, and after thus being ballooned around the package, the outer strand is joined with the strand from the inner package to form a wrapped or doubled yarn. In forming wrapped yarns, it is merely necessary to see that a different tension is applied to each of the yarns associated by the twisting system. However, in forming doubled or folded yarns of symmetrical construction, it has been necessary heretofore that the tension in each yarn be made substantially the same. For this purpose, it had already been suggested to provide such a system with a tension equalizer whereby an increase in tension in one of the yarns actuates the equalizing device to modify the tension of both yarns to restore them to substantially equal tensions. However, all such systems heretofore proposed have the disadvantages of being difficult to lace up when starting up the system, and frequently of exerting severe rubbing and frictional effects upon the yarns.

According to the present invention, the necessity to have each yarn under the same tension is avoided by providing a common yarn-feed control means comprising at least one rotatable idler roll about the peripheral surface of which the strands pass in non-slipping tractive engagement for directing or maintaining the feed of both or all of the yarns to the doubling point at substantially the same speed. A further object of the invention is to provide such a feed control arrangement of a construction adapted for rapid and easy lacing. Further objects and advantages will be apparent from the drawing to which reference is made hereinafter.

In the drawing illustrative of the invention,

Figure 1 shows in vertical elevation, partially in cross section, one embodiment of the invention;

Figure 2 is an end elevation, partially in section, showing a modification in a multiple end or multiple station machine;

Figure 3 is a detail view;

Figure 4 is a view similar to Figure 3, of a modification of the yarn-feeding means;

Figure 5 shows a modification for plying more than two strands.

Figure 6 shows a modification for doubling

2

strands proceeding from a single package in which they are wound side by side, and

Figure 7 shows diagrammatically a modification of Figure 6.

As shown in Figures 1 and 3, the doubling system of the present invention comprises a hollow twisting spindle 2 rotatably mounted in a support 3 and suitably driven preferably at substantially constant speed, such as by the pulley 10, belt 5 and motor 6. The hollow spindle 2 is mounted at an angle inclined to the vertical and at its upper end is provided with an anti-friction bearing for rotatably supporting a package carrier comprising a tapered member 7 adapted to fit inside the package which may in this instance be wound on the conical core 8, and an annular base 9 which may be weighted at 10 to prevent rotation of the package carrier during rotation of the spindle 2. Advantageously a shroud 11 and removable hood 12 may be provided to prevent interference between the yarns and too rapid unwinding of the yarn from the package therein caused by air currents set up by the ballooning yarn. A hollow guide 13 fits within the open end 14 of the form 7 and is arranged in alignment with the hollow spindle 2. This guide 13 is hollow and is recessed at 14 to permit the insertion of a spring tension element 15. The tension element 15 is held in place about the tubular guide 13 by means of a ring 16. An additional ring 17 may be moved back and forth to adjust the pressure of the spring element 15 against the portion of the guide 13 not cut away adjacent 14. A flyer 18 is secured to the spindle 2 between the package carrier and the support 3, and the hollow spindle is provided with an opening 19 adjacent the flyer. A balloon-controlling guide 20 is mounted on an arm 21 hinged to an extension 3a of the supporting structure. A tension device 40 22 and a pulley guide 23 are arranged to guide yarn from an outer package carried on a support 24.

There is secured to the lower end of the hollow spindle 2, an arm 25 carrying two canted idler rolls 26. The axes of these rolls extend across the axis of the spindle, so that the yarns proceed side by side out of the hollow spindle substantially parallel to each other and in substantially non-slipping tractive engagement about the two rolls 26 as a unit, the canted arrangement of the rolls assuring lateral displacement of the yarns to prevent rubbing contact with their courses passing directly to the rolls as would occur if the rolls 26 were mounted on parallel axes or a single idler roll were used. A take-up device 27 with

associated traverse guide 28 is arranged to be driven at a predetermined speed, such as by the pulleys 29 and 30, and belt 31. Pulley 38 may derive its power from the motor 6 through a reduction gearing 31a.

In operation of the device of Figures 1 and 3, the outer yarn travels about pulley 28 through the tension device 22 and associated guide 22a, through the ballooning guide 28, and then through a loop or balloon to the flyer 18, the opening 19 of the spindle 2 and through the hollow spindle to the rolls 26. At the same time, the yarn from the inner package proceeds through the guide 13 and then is guided longitudinally through a path extending through the tension device 18 through the spindle 2 to the rolls 26. The shroud 11 and hood 12 prevent interference between the yarns from the different packages. After the outer yarn enters the hollow spindle 2, it can be said to join the path of the inner yarn (for purposes of definition herein, this path is considered to be the hollow bore within the spindle 2) and the two yarns proceed substantially in the same general path side by side to the rolls 26 and about the rolls without being twisted together. Since the spindle 2 rotates with rolls 26 about the axis of the spindle, the idler roll assembly rotates as a unit about this axis and at the same speed as the spindle and the flyer carried thereby and doubling occurs approximately at the point where the two yarns leave the rolls 26 to proceed to the take-up 27. While the two yarns are not twisted together until they are about to leave the rolls 26, they are twisted about their individual axes in a direction opposite to the doubling or cabling twists of the plied yarns. Thus, if the spindle 2 is rotated in a clockwise direction as viewed from above, Z-twist is put into the individual yarns before they reach the rolls 26, but S-twist is present in the doubled structure, the combination of such twists in the final structure resulting in the lay of the fibers or filaments in the final structure being substantially parallel to the axis of the structure. Obviously, by rotating the spindle in the opposite direction, the final cord will have the opposite or Z-twist. The number of twists per inch in the final cord structure can be controlled by predetermining the relation between the speed of rotation of the spindle with respect to the speed of the take-up.

Figure 4 shows a modification of the yarn-feed control rolls in accordance with which two or more rolls 26a rotatably mounted on parallel axes arranged across the extended axis of the spindle 2 are carried by the arm 25. Three are actually shown in alignment so that the yarns proceed from the hollow spindle side by side in a sinuous path about each of the rolls in succession. Preferably the rolls, as in Figure 3, are open at one end and by thus being free of obstruction are readily laced. In addition, where a multiplicity of rolls are used as in Figure 4, each roll may have a shorter axial length than that of its immediate predecessor, which again facilitates lacing. The axes of the several rolls of Figure 4 may also be offset to increase the arc of contact with the yarns thereabout to assure non-slipping contact. The rolls 26 or 26a may be provided with grooves for receiving the yarn but this is not essential or preferred.

By using the yarn-controlling arrangement for directing them at the same speed to the doubling point, it is not essential that the tensions in the yarns as they proceed through the twisting device be the same. While the ideal situation

would be to have the same tension exerted upon each of the yarns, the use of the feeding means of the present invention allows considerable difference to be present in such tensions without such difference producing a noticeable effect upon the final doubled structure.

Referring to Figure 2, a modification is shown adapting the twister to a compact, efficient and convenient arrangement in a multiple-unit machine. As shown, the machine comprises a framework having central uprights 32 carrying a lower supporting platform 34 and upper supports 35. Such supports are carried on each side of the center of the machine as viewed endwise in Figure 2, and only the details of one side are shown in full and described hereinafter. A rail 36 having a plurality of supporting bearings 37, one for each hollow spindle 2 of each unit, extends the length of the machine above the intermediate platform 34. The pulleys 4 of the units are driven by a belt 5a operating in connection with the pulley 38 on the driving shaft 39 running the length of the machine. A guide rail 40 is provided to direct the yarn from the packages on the lower support 33 which may be arranged for transfer unwinding. The upper supports 35 carry guiding rotors 41, the resistance to rotation of which may be controlled by adjusting the finger screw 42 which varies the pressure of a drag block 43 against a disc 44 fixed to the shaft to which the roller 41 is secured. The packages on the lower support 33 and the associated guide 28a are offset longitudinally of the machine from the twisting unit which comprises a ballooning guide 28a for leading the outer strand thereto from the roller 41 which is directly over guide 28a. The doubled yarns proceed from the rollers 26 carried by the spindle 2 about a pair of canted rolls 45, which are rotatably mounted in a fixed position on a lever arm 46 in turn pivotally mounted on a upright 32. Arm 46 also carries a gear 48, which is driven by gear 49 carried by a driving shaft 50, the gear 48 serving to drive at least one of the rolls 45 at controlled speed. A traverse guide 51 controls the lay of the yarns upon the take-up 52, which may be driven by means of the cylinder 53 making peripheral contact therewith. A manual stop and start lever 54 is provided and is linked to the lever 55, which is fixedly secured to levers 46 and 56, such three-armed lever unit being pivotally mounted at 47 so that lever 55 controls the pivotal motion of lever 46 and lever 56. Lever 56 carries a belt-tensioning pulley 57 and a brake 58. Lever 54 also carries a pin 59, co-operating with the clutch-shifting member 60 for connecting the shaft 61 with the take-up driving cylinder 53. Lever 54 extends at an angle from its pivotal connection with lever 55, so that its direction makes a small angle with the plane of the drawing. In order to stop the machine, the operator gives the handle of the lever 54 a motion comprising a component longitudinally of the machine to disengage the clutch 60 and transverse of the machine toward the center thereof to rotate levers 55, 56 and 46 as a unit in a clockwise direction, thereby releasing the tension of pulley 57 against belt 5a, applying brake 58 to the pulley 4 and disengaging gear 48 from gear 49. The spring 62 plus the yarn tension maintains the parts in driving relationship. If either strand breaks the yarn tension is reduced. Rolls 45 then drop and stop the machine automatically by the sequence above.

In the embodiments shown, the means for con-

trolling the feed of the yarns at the same speed to the doubling position is shown below the hollow spindle. It is to be understood, however, that such feed-controlling means can be placed at any position of the spindle after the yarn from the outer package has entered the hollow spindle. Thus, in Figure 1, the hollow spindle may be given a somewhat longer extension between the bearing 3 and the flyer, so that there would be room for the rolls to be mounted below the opening 19 therein. Such an embodiment necessitates the cutting away of a part of the hollow spindle, however, and to this extent would be disadvantageous. Preferably, the feed-control means is arranged in the open beyond the lower end of the hollow spindle, where it is most accessible for lacing up, and does not require a cutting away of the spindle.

While the invention has been disclosed with respect to the doubling together of two yarns, it is applicable as well to the doubling together of more than two yarns. For example, the same twisting system may be employed by supporting a third package between the guide 20 and the inside package within the shroud 11. Such intermediate package would be supported on an extension of guide tube 13 (see modified tube 13a of Figure 5) and the yarn proceeding from it would pass down through tube 13a, and enter the end of spindle 2. The yarn from the lower package on the spindle would then pass up through a guide tube 73 with tension device 74 at the top of removable hood 12'. It would then balloon about both packages and enter spindle 2 at hole 19'. The yarn coming from the outer package such as that carried on the support 24 would be ballooned around both of the other packages at the same speed as the ballooning of the yarn from the package on the spindle and then all three yarns would be assembled in the hollow spindle 2 in advance of the rolls 26.

The system of the present invention is particularly applicable for the production of plied constructions by a method involving first the winding of two yarns or other strands side by side in a common package without intertwisting, upon a suitable core, such as a bobbin, cone, or drum, and then mounting the resulting two-strand package upon the spindle of the present invention, as illustrated in Figure 6. As there shown, the construction is substantially the same as in Figure 1, except that a yarn guiding tube 73 and a fixed tension device 74 are provided at the top of the removable hood 12b for a second strand which is led thereby out at the top and balloons down to the flyer 18 entering the hollow spindle 2 at hole 19. The first strand passes down tubular guide 13 as before. A third strand (as shown diagrammatically in Figure 7) may then be led through guide 20 and ballooned about the package to the other end of flyer 18 and enter the spindle from the side opposite the point of entry of the second strand. After the three strands reach a common path within the passage of the hollow spindle 2 they proceed about the feeding rolls 26 carried on arm 25 secured for rotation with the spindle. Since both yarns from the common package are used at the same rate, the utilization of the two-strand package is accompanied by excellent results, no difficulty being encountered by difference in speeds of unwinding of the strands from the package. The difference in lengths of the paths followed by the two strands can be compensated for during the initial lacing up of the system, so that the outer strand has an

additional length to provide the ballooning. The two ballooning strands cannot interfere with each other since they travel at the same speed and are held 180° apart by flyer 18.

5 In the specification and claims, the term "doubling" is intended to include the plying, folding, intertwisting, or twisting together of two or more than two individual strands and it is not intended to be restricted to the twisting together of 10 two strands.

It is to be understood that changes and variations may be made without departing from the spirit and scope of the invention, as defined by the appended claims.

15 I claim:

1. The method of producing a plied strand construction comprising the steps of winding two strands side by side on a core, guiding one of the strands from the package longitudinally through a path, guiding the other strand through a loop about the package and then along the path of the first strand, directing the strands longitudinally through the common portion of said path substantially at the same speed to an intertwisting position and simultaneously rotating the strands in advance of the intertwisting position about a common axis.

2. The method of producing a plied strand construction comprising the steps of winding two strands side by side on a hollow core, guiding one of the strands from the package through the hollow core and then longitudinally through a path, guiding the other strand through a loop about the package and then along the path of the first strand, directing the strands longitudinally through the common portion of said path substantially at the same speed to an intertwisting position and simultaneously rotating the strands in advance of the intertwisting position about a common axis.

3. The method of producing a plied strand construction comprising the steps of winding two strands side by side on a hollow core, guiding one of the strands from the package through the hollow core and then longitudinally through a path, guiding the other strand through a loop about the package and then along the path of the first strand, guiding a third strand through a loop about the package and then along the adjacent paths of the first two strands, directing the strands longitudinally through the common portion of said path substantially at the same speed to an intertwisting position and simultaneously rotating the strands in advance of the intertwisting position about a common axis.

4. The method of producing a plied strand construction comprising the steps of winding each of a plurality of strands to form a separate package, disposing two of the packages in proximity to each other, guiding the strand from one of the two packages longitudinally through the other of the two packages and then through a path beyond the latter package, guiding the strand from the latter package through a loop around the former package, then back through a loop around both packages and then along the path of the first strand, directing the strands longitudinally through the common portion of said path substantially at the same speed to an intertwisting position and simultaneously rotating the strands in advance of the intertwisting position generally about a common axis.

5. The method of producing a plied strand construction comprising the steps of winding each of a plurality of strands to form a separate

package, disposing two of the packages in proximity to each other, guiding the strand from one of the two packages longitudinally through the other of the two packages and then through a path beyond the latter package, guiding the strand from the latter package through a loop around the former package, then back through a loop around both packages and then along the path of the first strand, guiding a strand from a third package through a loop about the first two packages and then along the path common to the first two strands, directing the strands longitudinally through said path substantially at the same speed to an intertwisting position and simultaneously rotating the strands in advance of the intertwisting position generally about a common axis.

6. Apparatus for doubling together a plurality of strands to form a plied construction comprising supply means for a plurality of strands, a hollow spindle, means for rotating the spindle, a carrier for supporting the supply means for at least one strand on the spindle, means for preventing rotation of the carrier during rotation of the spindle, a flyer secured to the spindle for rotating at least one other strand in a loop about the supply means carried on the spindle, and idler roller means carried by the spindle for rotation therewith for maintaining the feed of the strands from the supply means on the carrier and from the loop thereabout longitudinally to the doubling position substantially at the same speed, each idler roll of said idler roll means being arranged to receive all of the strands in substantially non-slipping, tractive engagement about at least a portion of its peripheral surface.

7. Apparatus for doubling together a plurality of strands to form a plied construction comprising supply means for a plurality of strands, a hollow spindle, means for rotating the spindle, a carrier for supporting the supply means for at least one strand on the spindle, means for preventing rotation of the carrier during rotation of the spindle, a flyer secured to the spindle for rotating at least one other strand in a loop about the supply means carried on the spindle, and at least one idler roll rotatably mounted on an axis transversely of the axis of the spindle carried by the spindle for bodily rotation therewith and arranged to receive the strands about its peripheral surface in substantially non-slipping, tractive engagement for maintaining the feed of the strands from the supply means on the spindle and from the loop thereabout longitudinally to the doubling position substantially at the same speed.

8. Apparatus for doubling together a plurality of strands to form a plied construction comprising supply means for a plurality of strands, means for guiding the strands to a doubling position, means for rotating the strands about their axes without doubling them in advance of the doubling position, and means for maintaining the feed of the strands at substantially the same speed to the doubling position comprising at least one rotatable idler roll arranged to receive all the strands and about the peripheral surface of which the strands pass substantially in non-slipping, tractive engagement, said feed-maintaining means being arranged to be rotated bodily about the axis of doubling to prevent doubling in advance of the doubling position, said idler roll being supported at one end only

and having its other end unobstructed to facilitate lacing up.

9. Apparatus for doubling together a plurality of strands to form a plied construction comprising supply means for a plurality of strands, means for guiding the strands to a doubling position, means for rotating the strands about their axes without doubling them in advance of the doubling position, and means for maintaining the feed of the strands at substantially the same speed to the doubling position comprising a plurality of rotatable idler rolls each being arranged to receive all of the strands, the several rolls being so positionally disposed with respect to each other as to assure substantially non-slipping, tractive engagement of the strands on at least one of the rolls, said feed-maintaining means being arranged to be rotated bodily about the axis of doubling to prevent doubling in advance of the doubling position, said rotatable elements being supported at one end only and having their other ends unobstructed to facilitate lacing up.

10. Apparatus for doubling together a plurality of strands to form a plied construction comprising supply means for a plurality of strands, a hollow spindle, means for rotating the spindle, a carrier for supporting supply means for at least one strand on the spindle, means for preventing rotation of the carrier during rotation of the spindle, a flyer secured to the spindle for rotating at least one other strand in a loop about the supply means carried on the spindle, an arm secured to the spindle, and a plurality of idler rolls rotatably mounted on the arm on axes transverse that of the spindle for maintaining the feed of the strands longitudinally to the doubling position substantially at the same speed.

11. Apparatus for twisting together a plurality of strands to form a plied construction comprising a plurality of supply packages, means for guiding a strand from one of the packages longitudinally through a path, means for guiding a strand from a second package in a loop about the first package and back in a loop about the first and second packages approximately to the path of the first strand, means beyond the path juncture for maintaining the feed of the strands longitudinally substantially at the same speed to a plying position and for simultaneously rotating the strands in advance of the plying position so as to put in a twist opposite to the ply twist, said feed-maintaining and strand-rotating means comprising at least one rotatable idler roll about the peripheral surface of which the strands pass substantially in non-slipping, tractive engagement.

12. Apparatus for twisting together a plurality of strands to form a plied construction comprising a plurality of supply packages, means for guiding a strand from one of the packages longitudinally through a path, means for guiding a strand from a second package in a loop about the first package and back in a loop about the first and second packages approximately to the path of the first strand, means for guiding a strand from a third package in a loop about the first two packages approximately to the point of juncture of the first two strands, means beyond the path juncture for maintaining the feed of the strands longitudinally substantially at the same speed to a plying position and for simultaneously rotating the strands in advance of the plying position so as to put in a twist opposite to the ply twist, said feed-maintaining and strand-rotat-

ing means comprising at least one rotatable idler roll about the peripheral surface of which the strands pass substantially in non-slipping, tractive engagement.

13. Apparatus for doubling together a plurality of strands to form a plied construction comprising supply means for a plurality of strands, a hollow spindle, means for rotating the spindle, a carrier for supporting the supply means for at least one strand on the spindle, means for preventing rotation of the carrier during rotation of the spindle, a flier secured to the spindle for rotating at least one other strand in a loop about the supply means carried on the spindle, an arm secured to the spindle, and a pair of canted idler rolls rotatably mounted on the arm on axes transverse that of the spindle for receiving all of the strands in substantially non-slipping, tractive engagement about each of their peripheral surfaces and for maintaining the feed of the strands longitudinally to the doubling position substantially at the same speed, said rolls being supported on one end only leaving the other end unobstructed to facilitate lacing up.

14. Apparatus for doubling together a plurality of strands to form a plied construction comprising supply means for a plurality of strands, a hollow spindle, means for rotating the spindle, a carrier for supporting the supply means for one strand on the spindle, means for preventing rotation of the carrier during rotation of the spindle, a flier secured to the spindle for rotating at least one other strand in a loop about the supply means carried on the spindle, an arm secured to the spindle, and a plurality of idler rolls rotatably mounted on the arm on axes transverse that of the spindle for maintaining the feed of the strands longitudinally to the doubling position substantially at the same speed, said rolls being supported on one end only leaving the other end unobstructed to facilitate lacing up and each of the rolls being of progressively lesser axial length in the direction of travel of the strands.

15. Apparatus for doubling together a plurality of strands to form a plied construction comprising a plurality of supply packages, means for guiding a strand from one of the packages longitudinally through a path, means for guiding a strand from at least one other package in a loop about the first package approximately to the path of the other strand, means beyond the path juncture for maintaining the feed of the strands longitudinally substantially at the same speed to a doubling position and for simultaneously rotating the strands in advance of the doubling position about a common axis, said feed-maintaining and strand-rotating means comprising at least one rotatable idler roll about the peripheral surface of which the strands pass substantially in non-slipping, tractive engagement.

16. Apparatus for doubling together a plurality of strands to form a plied construction comprising supply means for a plurality of strands, means for guiding one of the strands longitudinally through a path, means for guiding at least one other strand in a loop about the supply means for both strands approximately to the path of the first strand, means beyond the path juncture for maintaining the feed of the strands longitudinally substantially at the same speed to a doubling position and for simultaneously rotating the strands in advance of the doubling position about a common axis, said feed-maintaining and strand-rotating means comprising at least

one rotatable idler roll about the peripheral surface of which the strands pass substantially in non-slipping, tractive engagement.

17. Apparatus for doubling together a plurality of strands to form a plied construction comprising common supply means for a plurality of strands, means for guiding one of the strands longitudinally through a path, means for guiding a second strand in a loop about the supply means for both strands approximately to the path of the first strand, means for guiding a third strand from a more remote package in a loop about the common supply means of the first two strands to the point of juncture of said strands, means beyond the path juncture for maintaining the feed of the strands longitudinally substantially at the same speed to a doubling position and for simultaneously rotating the strands in advance of the doubling position about a common axis, said feed-maintaining and strand-rotating means comprising at least one rotatable idler roll about the peripheral surface of which the strands pass substantially in non-slipping, tractive engagement.

18. Apparatus for doubling together a plurality of strands to form a plied construction comprising a plurality of strand supply packages, a hollow spindle, means for rotating the spindle, a carrier for supporting one of the packages on the spindle, means for preventing rotation of the carrier during rotation of the spindle, a flier secured to the spindle for rotating at least one other strand from another package in a loop about that carried on the spindle, and at least one idler roll rotatably mounted on an axis transversely of the axis of the spindle carried by the spindle for bodily rotation therewith and arranged to receive the strands about its peripheral surface in substantially non-slipping, tractive engagement for maintaining the feed of the strands from the package on the spindle and from the loop thereabout longitudinally to the doubling position substantially at the same speed.

19. Apparatus for doubling together a plurality of strands to form a plied construction comprising a plurality of strand supply packages, means for guiding the strands to a doubling position, means for rotating the strands about their axes without doubling them in advance of the doubling position, and means for maintaining the feed of the strands at substantially the same speed to the doubling position comprising at least one rotatable idler roll arranged to receive all the strands and about the peripheral surface of which the strands pass substantially in non-slipping, tractive engagement, said feed-maintaining means being arranged to be rotated bodily about the axis of doubling to prevent doubling in advance of the doubling position, said rotatable element being supported at one end only and having its other end unobstructed to facilitate lacing up.

20. Apparatus for doubling together a plurality of strands to form a plied construction comprising a plurality of strand supply packages, a hollow spindle, means for rotating the spindle, a carrier for supporting at least one of the packages on the spindle, means for preventing rotation of the carrier during rotation of the spindle, a flier secured to the spindle for rotating at least one other strand from another package in a loop about such packages as are carried on the spindle, an arm secured to the spindle, and a plurality of idler rolls rotatably mounted on the arm on axes transverse that of the spindle for

receiving all of the strands in substantially non-slipping, tractive engagement about each of their peripheral surfaces and for maintaining the feed of the strands longitudinally to the doubling position substantially at the same speed.

21. Apparatus for doubling together a plurality of strands to form a plied construction comprising a plurality of strand supply packages, a hollow spindle, means for rotating the spindle, a carrier for supporting at least one of the packages on the spindle, means for preventing rotation of the carrier during rotation of the spindle, a flyer secured to the spindle for rotating at least one other strand from another package in a loop about such packages as are carried on the spindle, an arm secured to the spindle, and a pair of canted idler rolls rotatably mounted on the arm on axes transverse that of the spindle for receiving all of the strands in substantially non-slipping, tractive engagement about each of their peripheral surfaces and for maintaining the feed of the strands longitudinally to the doubling position substantially at the same speed, said rolls being supported on one end only leaving the other end unobstructed to facilitate lacing up.

22. Apparatus for doubling together a plurality of strands to form a plied construction comprising a plurality of strand supply packages, a hollow spindle, means for rotating the spindle, a carrier for supporting at least one of the packages on the spindle, means for preventing rotation of the carrier during rotation of the spindle, a flyer secured to the spindle for rotating at least one other strand from another package in a loop about such packages as are carried on the spindle, an arm secured to the spindle, and a plurality of idler rolls rotatably mounted on the arm on axes transverse that of the spindle for maintaining the feed of the strands longitudinally to the doubling position substantially at the same speed, said rolls being supported on one end only leaving the other end unobstructed to facilitate lacing up and each of the rolls being of progressively lesser axial length in the direction of travel of the strands.

23. Apparatus for doubling together a plurality of strands to form a plied construction comprising supply means for a plurality of strands, means for guiding one of the strands longitudinally through a path, rotatable means for guiding at least one other strand in a loop about the supply means for the first strand to the path of the first strand, idler roll means rotatable as a unit about the same axis as the rotatable guiding means and disposed, with the axis of each roll thereof extending generally transversely of the first-mentioned axis of rotation beyond the path juncture for maintaining the feed of the strands longitudinally substantially at the same speed to a doubling position beyond the feed-maintaining means and for simultaneously rotating the strands in advance of the doubling position about a common axis, each idler roll of said idler roll means being arranged to receive all of the strands in substantially non-slipping, tractive engagement about at least a portion of its peripheral surface, and means for rotating the guiding means and idler roll means about their common axis at the same speed of rotation.

24. Apparatus for doubling together a plurality of strands to form a plied construction com-

prising supply means for a plurality of strands, take-up means, means for guiding one of the strands longitudinally through a path to the take-up means, rotatable means for guiding at least one other strand in a loop about the supply means for the first strand and then along the path of the first strand to the take-up means, idler roll means rotatable as a unit about the same axis as the rotatable guiding means and disposed, with the axis of each roll thereof extending generally transversely of the first-mentioned axis of rotation, in the generally common portion of the path of the strands for maintaining the feed of the strands longitudinally alongside each other substantially at the same speed to a doubling position beyond the feed-maintaining means and in advance of the take-up means and for simultaneously rotating the strands in advance of the doubling position about a common axis, each idler roll of said idler roll means being arranged to receive all of the strands in substantially non-slipping, tractive engagement about at least a portion of its peripheral surface, and means for rotating the guiding means and idler roll means about their common axis at the same speed of rotation.

25. Apparatus for doubling together a plurality of strands to form a plied construction comprising supply means for a plurality of strands, means for guiding one of the strands longitudinally through a path, rotatable means for guiding at least one other strand in a loop about the supply means for the first strand to the path of the first strand, idler roll means rotatable as a unit about the same axis as the rotatable guiding means and disposed, with the axis of each roll thereof extending generally transversely of the first-mentioned axis of rotation, beyond the path juncture for maintaining the feed of the strands longitudinally substantially at the same speed to a doubling position and for simultaneously rotating the strands in advance of the doubling position about a common axis, said feed-maintaining and strand-rotating means comprising at least one rotatable element about the peripheral surface of which the strands pass substantially in non-slipping, tractive engagement, and means for rotating the guiding means and idler roll means about their common axis at the same speed of rotation.

SEDDON C. NELSON.
